UNITED STATES PATENT OFFICE

146,313

DESIGN FOR A RAILWAY VEHICLE

Stanley W. Kay, Chicago, Ill., assignor to Pullman-Standard Car Manufacturing Company, Chicago, Ill., a corporation of Delaware

Application July 7, 1945, Serial No. 120,549

Term of patent 14 years

(Cl. D66—1)

To all whom it may concern:

Be it known that I, Stanley W. Kay, a citizen of the United States, residing at Chicago, in the county of Cook, and State of Illinois, have invented a new, original, and ornamental Design for Railway Vehicle, of which the following is a specification, reference being had to the accompanying drawings, forming part thereof.

In the drawings—

Fig. 1 is a perspective view of a vehicle with portions broken away better to reveal my new design and looking into the interior of the vehicle to show the recreation room in a generally transverse direction;

Fig. 2 is a perspective view of the recreation room showing my new design but looking into the room in a generally longitudinal direction;

Fig. 3 is a plan view of a vehicle equipped with a recreation room in accordance with my new design and showing the general layout and arrangement of the recreation room; and

Fig. 4 is a general perspective view of a conventional railway vehicle of the type in which my new design is incorporated.

The characteristic features of the present design are shown by means of full lines in the drawings and reside in the recreation room in the interior portions of the vehicle.

I claim:

The ornamental design for a railway vehicle, substantially as shown and described.

STANLEY W. KAY.
